Patented Dec. 14, 1926.

UNITED STATES PATENT OFFICE.

GEORGE H. PAGE, OF WINNIPEG, MANITOBA, CANADA.

TEE MOLDER.

Application filed May 18, 1925. Serial No. 31,223.

The invention relates to improvements in tee molders and an object of the invention is to provide a simple tool by the use of which one can quickly and easily make a sand tee such as is required to support a golf ball when playing the game, the finished tee being compact and shaped to receive the ball and support it in an elevated position.

A further object is to construct the tool 10 in a simple, inexpensive and durable manner and so that it will be light and compact and easily operated.

A further object is to construct a tool which will not only receive and shape the 15 sand placed therein but will also, when brought into contact with the green and actuated, compress the sand so that the finished tee is firm and leave a pocket therein for the reception of the ball.

With the above more important objects in view the invention consists essentially in the arrangement and construction of parts hereinafter more particularly described, reference being had to the accompanying drawings 20 in which:

Fig. 1 is a side view of the tee molder.

Fig. 2 is a plan view thereof.

Fig. 3 is a longitudinal vertical sectional view centrally through the molder, the sections being taken at the line 3-3' Figure 1.

Figure 4 is an enlarged detailed cross sectional view at 4-4' Figure 3.

Fig. 5 is a perspective view of the tee.

In the drawing like characters of reference 35 indicate corresponding parts in the several figures.

The body 1 of the tee mold or maker is tubular and it is provided with an internal seat 2 adjacent the lower end and has the lower 40 end thereof outwardly flared as indicated at 3 and provided with an internal frusto-conical shaped molding pocket 4. Adjoining the upper end, the body is supplied with a pair of diametrically opposing finger grips 5 and 45 6. A washer or disc 7 is inserted within the body being put in through the upper end thereof and when finally in place, the washer seats on the shoulder and is prevented from rotating in any suitable manner. I have 50 herein shown the disc as supplied with diametrically opposing outstanding lugs 8 and 9 which are adapted to be received within channels 10 and 11 cut in the wall of the body piece. The channels receive the lugs 55 and permit the washer to slide down into

place and also prevent rotation of the seated washer.

The washer is provided with a central hole 12 presenting V-shaped corners and the hole receives a stem 13 having threads of considerable pitch, the threads operating in the V-shaped corners of the hole 12. The stem can be formed from a bar of metal, square in cross section, which is twisted and after twisting, the four corners of the bar form the 60 spiral threads which operate in the corners of the hole 12. The lower end of the stem passes freely into the lower end of the body piece and terminates in a centrally positioned stud 14 on which I mount a tampon head 70 15 which is of a frusto-conical shape complementary to the pocket 4 and has the lower end thereof convex as indicated at 16. The head is held permanently to the stem by riveting the lower end of the stud. The upper 75 end of the stem terminates also in a stud 17 and projects beyond the upper end of the body piece. A sleeve 18 is also provided and this slidably enters the upper end of the body piece and freely receives the upper end 80 of the stem.

The upper end of the sleeve terminates in a knob 19 which is drilled and screw threaded and receives a screw 20. It will be observed 85 that there is an internal shoulder 21 provided in the knob and a space 22 reserved between the shoulder and the screw. In this space, a washer 23 is placed, the washer being mounted on the stem 17, the upper end of which is enlarged or riveted as indicated at 90 24 to retain the washer. A coil spring 25 is inserted between the disc 7 and the lower end of the sleeve, this spring operating to normally hold the head 15 seated in the upper 95 end of the pocket 4. The normal position of the disc is best shown in Figure 3 and according to the arrangement, it will be apparent that when one grasps the finger pieces 5 and 6 with his finger and places the knob in the palm of his hand and presses 100 down on the knob, such will result in the down movement of the head 15 and also in a rotary movement of the head due to the threads of the stem being rotated by the disc. During this movement the knob 19 does not 105 turn as the stem is free to rotate in respect to the knob due to the top fastening.

I have found in actual practice that approximately one quarter of an inch is all the down movement that one requires to give 110

the head and this movement is limited by having the knob strike the upper end of the body piece when the knob has been moved down approximately one quarter of an inch. 5 The amount which the head 15 is rotated is approximately one quarter of a revolution.

Whilst I have stated one quarter inch end movement and one quarter of a revolution of the head, it will be readily understood 10 that I do not desire to be limited to these amounts. They are only suggested so that the action of the device may be better understood.

When it is desired to make a sand tee such 15 as is required when playing golf, one fills the molding pocket 4 with sand, the parts at this time being in the position as shown in Figure 3. He, then, places the device on the green in an upright position with the 20 lower end contacting with the green and presses down on the knob whilst gripping the finger pieces with the fingers. The down movement of the knob causes the head 15 to move down and simultaneously turn and this 25 movement firmly packs the sand to form the tee as indicated at 26 and provides the tee with a shallow saucer shaped pocket 27 which is adapted to receive the ball. The tee 30 so formed will retain its shape and will not crumble under the weight of the ball when the same is placed in the pocket. The device 35 will be made light and compact so that it can be readily carried about. The frusto-conical shape of the pocket 4 shapes the sides of the tee as will be readily understood.

Whilst I have entered into a detailed description of the manner in which the stem is depressed and caused to be rotated when being depressed, it will be readily understood 40 that the construction might be materially modified without departing from the spirit of the invention as set forth in the appended claims.

By arranging the parts as herein shown, 45 it is a very easy matter to take the article apart for repair or other purposes as one simply has to remove the screw 20 and cut off the flared head of the stud 17. This permits the sleeve to be withdrawn upwardly 50 and the stem pulled out from the bottom after which the spring and washer 7 can be removed. The stem 17 is made sufficiently long so that it can be subsequently re-riveted upon the parts being again re-assembled.

What I claim as my invention is:

55

1. A sand tee molder having a sand receiving and molding pocket, a head normally positioned in the pocket at the inner end thereof, and means for rotating and simultaneously shifting said head toward the mouth of 60 the pocket.

2. A sand tee molder having a frusto-conical shaped sand receiving and molding pocket in the lower end thereof, a depressible head in the small end of the pocket and 65 means for turning the head as it is depressed.

3. A sand tee molder having a frusto-conical shaped sand receiving and molding pocket in the lower end thereof, a depressible head normally closing the small end of the 70 pocket and having the lower end thereof convex and means for turning the head as it is depressed.

4. A sand tee molder comprising a tubular body member having the lower end thereof 75 terminating in a frusto-conical sand receiving and molding pocket, a stem contained within the body member, means for turning the stem upon the same being end shifted, a head secured to the lower end of the stem 80 and adapted to close the upper end of the molding pocket, a spring acting on the stem and normally holding the head seated in the pocket and a knob associated with the stem for depressing the same. 85

5. A sand tee molder comprising a tubular body piece having the lower end thereof presenting a frusto-conical shaped sand receiving mold, an endwise shiftable stem extending within the body piece, means for turning 90 the stem in the end shifting thereof, a head secured to the lower end of the stem and normally closing the upper end of the pocket, said head having the under face thereof convex, a sleeve slidably entering the upper end 95 of the body piece and freely receiving the upper end of the stem, said sleeve having the upper end thereof terminating in a knob, means connecting the upper end of the stem to the knob whilst permitting of the rotation 100 of the stem in respect to the knob and a coil spring contained within the body piece and engaging the stem and normally holding the head seated in the upper end of the pocket.

Signed at Winnipeg this 7th day of May 1925.

GEORGE H. PAGE.
